US00D700274S

(12) **United States Design Patent**
Knight et al.

(10) **Patent No.:** **US D700,274 S**
(b4) **Date of Patent:** **** Feb. 25, 2014**

(54) **HYPPOCHLORITE INJECTOR**

- (71) Applicant: **Severn Trent De Nora, LLC**, Sugar Land, TX (US)
- (72) Inventors: **Larry Knight**, Sugar Land, TX (US); **Rudolf Matousek**, Richmond, TX (US); **William Burroughs**, Sealy, TX (US); **Lucette Falcon**, Houston, TX (US)
- (73) Assignee: **Severn Trent De Nora, LLC**, Sugar Land, TX (US)
- (**) Term: **14 Years**
- (21) Appl. No.: **29/453,774**
- (22) Filed: **May 2, 2013**
